UNITED STATES PATENT OFFICE.

NORMAN F. STEVENS, OF LOS ANGELES, CALIFORNIA.

DESIGN FOR A LIGHTING FIXTURE.

Application filed August 29, 1925. Serial No. 14,640. Term of patent 3½ years.

To all whom it may concern:

Be it known that I, NORMAN F. STEVENS, a citizen of the United States, residing at Los Angeles, in the county of Los Angeles and State of California, have invented a new, original, and ornamental Design for Lighting Fixtures, of which the following is a specification, reference being had to the accompanying drawing, forming a part thereof.

In the accompanying drawings, Fig. 1 is an elevation of an ornamental lighting fix-

ture embodying the features of my invention;

Fig. 2 is a side elevation of the supporting member thereof, and

Fig. 3 is a side elevation of the back plate used in the complete design, as shown in Fig. 1.

I claim:

The ornamental design for a lighting fixture substantially as shown.

NORMAN F. STEVENS.
